ATTORNEY

UNITED STATES PATENT OFFICE

HENRY O. SWANN, OF HATTIESBURG, MISSISSIPPI

GUARD FOR ADZES

Application filed November 15, 1930. Serial No. 495,966.

The object of the invention is to provide a device adapted for attachment to the conventional adze whereby the workman will be prevented from cutting his leg or foot in the use of the tool in the event of the latter slipping as is frequently the case; to provide a guard which may be readily attached to the conventional adze and spaced the desired distance from the blade; to provide a device of this character which may be readily adjusted to maintain its relation with respect to the cutting edge as the adze is reduced in length due to sharpening or the like; and generally to provide a device of the character indicated which is of simple form and therefore susceptible of cheap manufacture.

With this object in view, the invention consists in a construction and combination of parts of which a preferred embodiment is illustrated in the accompanying drawings, wherein:

Figure 1 is a top plane view of the conventional adze with the invention applied in operative position thereon.

Figures 2 and 3 are respectively end and side elevations of the structure shown in Figure 1.

Figure 4 is a sectional view on the plane indicated by the line 4—4 of Figure 1.

The conventional adze 10 has the handle attaching eye formed in an upward extension 11 and it is to this latter that the guard constituting the invention is attached. The guard proper consists preferably of a metal rod bent to provide the cutting edge shielding portion 12 and the legs 14, the latter following the side edges of the blade of the adze and the former the cutting edge thereof. The legs are offset inwardly back of the blade portion of the tool, as indicated at 15, and these offset portions are threaded, being extended through eyes formed in cross-heads 16 and 17 which are recessed as indicated at 18 to provide seats in which the extension 11 rests. Nuts 19 threaded on the offset portions 15 engage the cross-heads on opposite faces and thus serve to bring them in clamping relation with the extension 11.

Set-screws 20 and 21 are threaded centrally through the cross-heads 16 and 17 respective-

ly and engaged in countersinks 22 formed in the outer surfaces of the end walls of the extension 11.

While the clamping relation of the cross-heads on the extension 11 may be generally relied upon to maintain the desired position of the guard, the set-screws 20 and 21 constitute means for positively insuring its position, since with them set in the countersinks, the cross-heads may not slide up or down the extension.

The nuts 19 while constituting means for effecting the clamping function of the cross-heads with the extension 11 also constitute means for adjusting the guard proper so that the shielding portion 12 will be disposed in proper relation to the cutting edge of the tool and as the latter wears and is sharpened, the guard may be adjusted backwardly to maintain its proper relative position with reference to the cutting edge by backing off those nuts 19 which engage the cross-head 16 and screwing forward the nuts which engage the cross-head 17.

Preferably the extension 11 is provided with series of counter-sinks 22 on the end walls thereof with those in each series arranged in superposed relation and by this means the guard may be adjusted toward and away from the blade by the proper selection of the counter-sinks with which the screws 20 and 21 are engaged.

By the provision of a guard, such as described, with a guard section paralleling the cutting edge of the blade, should the tool slip when being used, the guard section will prevent its penetration into the leg or foot of the workman.

The invention having been described, what is claimed as new and useful is:

1. In combination with an adze, a guard laterally spaced from but positioned to parallel the cutting edge of the latter and prevent its penetration into the limb of the user.
2. In combination with an adze, a guard removably attached to the adze and having a cutting edge shielding portion arranged in spaced relation laterally to the cutting edge of the adze.
3. In combination with an adze, a guard at-

- attachable to the same and having a cutting edge shielding portion parallelling but laterally spaced from the cutting edge of its blade, said guard being adjustable to maintain the desired relation of the shielding portion and the cutting edge of the adze as the latter is reduced by sharpening.
4. In combination with an adze, a guard attachable to the latter in laterally spaced relation to the blade thereof and having a cutting edge shielding portion, the guard being adjustable toward and away from the adze blade.
5. In combination with an adze, a guard attachable to the latter in laterally spaced relation to the blade thereof and having a cutting edge shielding portion, the guard being adjustable toward and away from the adze blade and adjustable longitudinally of the blade.
- 20 6. In combination with an adze, a guard attachable to the latter in laterally spaced relation to the blade thereof and having a cutting edge shielding portion, the guard being adjustable toward and away from the adze blade and rearwardly to compensate for reduction in the length of the blade due to sharpening.
7. In combination with an adze, a guard 30 having a cutting edge shielding portion and connected legs, and cross-heads spanning the eye portion of the adze, said legs extending through the cross-heads and the latter being clamped on the eye portion.
- 35 8. In combination with an adze, a guard having a cutting edge shielding portion and connected legs, and crossheads spanning the eye portion of the adze, said legs extending through the cross-heads and the latter being 40 clamped on the eye portion, and set-screws passing through the cross-heads and bearing against the end walls of the eye portions.
9. In combination with an adze, a guard 45 having a cutting edge shielding portion and connected legs, cross-heads spanning the eye portion of the adze, the legs extending through said cross-heads and being exteriorly threaded in the region thereof, and nuts carried on said threaded portions and bearing against 50 opposite faces of the cross-heads.
10. In combination with an adze, a guard 55 having a cutting edge shielding portion and connected legs, cross-heads spanning the eye portion of the adze on opposite ends, said legs extending through said cross-heads and being exteriorly threaded in the region thereof, nuts carried on the threaded portions of the legs and bearing against opposite faces of the cross-heads, and set-screws passing centrally 60 through the cross-heads and bearing upon the eye portion of the adze.
11. In combination with an adze, a guard 65 having a cutting edge shielding portion and connected legs, cross-heads spanning the eye portion of the adze on opposite ends, said legs

extending through said cross-heads and being exteriorly threaded in the region thereof, nuts carried on the threaded portions of the legs and bearing against opposite faces of the cross-heads, and set-screws passing centrally 70 through the cross-heads and bearing upon the eye portion of the adze, said eye portion being provided with series of counter-sinks of which those in each series are arranged in superposed relation for selective engagement by 75 the set-screws.

In testimony whereof he affixes his signature.
